UNITED STATES PATENT OFFICE

116,342

DESIGN FOR A CUFF LINK

George A. Ingleby, Cranston, R. I., assignor to
The Hadley Company, Inc., Providence, R. I., a corporation of Rhode Island

Application June 23, 1939, Serial No. 85,643

Term of patent 7 years

To all whom it may concern:

Be it known that I, George A. Ingleby, a citizen of the United States of America, residing at Cranston, in the county of Providence and State of Rhode Island, have invented a new, original, and ornamental Design for a Cuff Link, of which the following is a specification, reference being had to the accompanying drawing, forming a part thereof.

Fig. 1 is an enlarged perspective view of a cuff link embodying my design; and Figs. 2 and 3 are front and side views, on a reduced scale, of the cuff link shown in Fig. 1.

I claim:

The ornamental design for a cuff link, substantially as shown.

GEORGE A. INGLEBY.
